Attorney

UNITED STATES PATENT OFFICE.

JOHN HENRY LEPFER, OF MASON CITY, IOWA.

HEATING MEANS FOR CARBURETORS.

1,222,426.

Specification of Letters Patent. Patented Apr. 10, 1917.

Application filed June 27, 1915. Serial No. 102,179.

To all whom it may concern:

Be it known that I, JOHN HENRY LEPFER, a citizen of the United States, residing at Mason City, in the county of Cerro Gordo and State of Iowa, have invented certain new and useful Improvements in Heating Means for Carburetors; and I do hereby declare the following to be a full, clear, and exact description of the invention, such as 10 will enable others skilled in the art to which it appertains to make and use the same.

This invention relates to heating means for carburetors, and has for one of its objects the provision of a heating device which 15 can be readily attached to any of the carburetors now in use by simply forming an internally screw threaded opening in a wall of the carburetor at any desired point, or which heating device may be embodied as 20 an associated part during the manufacture of the carburetor.

Another object of this invention is the provision of a closed heater for carburetors, having heating coils arranged therein and 25 connected in circuit with any suitable source of electrical supply for energizing the coils for rendering the heater active for heating the liquid fuel contained in the carburetor to the required temperature for maintaining the liquid fuel in condition for the more 30 complete admixture and combustion of the same in cold weather.

A further object of this invention is the provision of a heater so constructed that 35 the same will be projected into and submerged within the body of the liquid fuel contained in the carburetor for exposing the greatest possible area of the heating surfaces of the heater to the liquid fuel for 40 attaining a maximum degree of efficiency from the minimum amount of heat units expended.

These and other objects and advantages will more fully appear as the nature of the 45 invention is more clearly understood from the following specification, the subject matter of the claims, and the views illustrated in the accompanying drawings, in which,

50 Figure 1 is a side view of a carburetor showing the invention in applied operative position thereon.

Fig. 2 is a vertical sectional view through the heating device, and the adjacent wall of 55 the carburetor shown partly broken away, showing the detail construction thereof.

Referring to the drawings, wherein similar reference characters denote corresponding parts throughout the several views, 1 denotes the carburetor bowl, or the oil well 60 thereof, having formed through a wall thereof the internally screw threaded opening 2, into which is screw threaded the externally screw threaded inner end 3 of the open ended plug or housing 4, provided adjacent its outer end with the wrench engaging nut 5, preferably of hexagonal conformation, whereby the plug or housing 4 may be efficiently mounted in the screw threaded opening 2 of the carburetor bowl 1 or removed therefrom through the medium of any suitable form of wrench.

The plug or housing 4 is formed with the longitudinal bore therethrough, the portion of the bore adjacent the inner end of the 75 plug or housing 4 being counterbored for a distance to provide the rear chamber 6 having smooth surrounding walls, while the portion of the bore adjacent the outer end of the plug or housing 4 is counterbored for a 80 distance to provide a front chamber which is subsequently formed with the surrounding screw threaded wall 7. The inner ends of the respective counterbores terminate at a sufficient distance from each other to provide the substantially centrally disposed annular rib or abutting shoulder 8.

Positioned within the plug or housing 4 is the elongated hollow cylindrical heater 9, provided with the closed inner end 10, and provided at its outer end with the right angularly disposed annular flange 11, from the periphery of which extends the right angularly disposed hollow cylindrical cap 12, which surrounds and snugly embraces the enlarged annular head 13 of the insulating core 14, formed of porcelain, mica or other suitable insulating material, and upon the inner wall of the heater 9 and its closed end 10, and upon the wall of the flange 11 of the heater adjacent the head 13 of the insulating core 14, is the insulating lining 15.

Within the closed heater 9 is the heating coil 16, extending for the entire length of 105 the heater 9 and prevented from contacting with the walls of the heater by the insulating lining 15, and having the inner end thereof projecting centrally through the closed end 10 of the heater 9 and soldered, 110 brazed, or otherwise secured to the closed end 10 as shown at 17. The opposite or

outer end of the coil 16 is secured to the inner end of the metal core or stem 18 by passing the end of the coil through the longitudinal bore 19 formed in the inner end 5 of the core 18 and opening into the scarf or cut away portion 20, this end of the coil 16 is drawn through the bore 19 for a sufficient distance so that the same may be wrapped around the core 18 in the manner shown at 10 21 and is prevented from slipping off the inner end of the metal core 18 by the head 22 formed upon the inner end of the metal core 18.

The metal core 18 extends through the 15 longitudinal bore 23 formed centrally through the insulating core 14 with its head 22 positioned within the recess 24 formed in the inner end of the insulating core 14 and surrounding the inner end of the bore 20 23, and for retaining the metal core 18 and its head 22 operatively mounted within the insulating core 14, the metal core 18 is formed with the screw threaded outer end 25, upon which is screw threaded the cup 25 shaped nut 26 which engages the reduced outer end of the insulating core 14, and also threaded upon the end 25 of the metal core 18 is the wire binding nut 27 and the lock nut 28 for engaging the outer face of the 30 binding nut 27 for preventing its casual rotation.

The heater 9 and its coil 16, the insulating core 14 and the metal core 18 therein, form, when assembled together, a substantially unitary structure, and these parts are inserted or projected into and through the plug or housing 4 in a manner so that the head 13 of the insulating core 14 will be positioned within the front chamber 7 of the plug 4, 40 and the heater 9 will project through the central bore of the plug 4 and the rear chamber 6 and suspended therein in spaced relation from the inner surrounding walls of the plug 4, the heater 9 preferably projecting for a distance beyond the inner end 45 of the plug or housing 4, and for retaining these parts in their respective operative positions within the plug or housing 4, the bushing 29 is provided.

50 The bushing 29 is formed with a smooth inner wall for snugly engaging the cap 12 of the heater 9, within which is snugly seated the head 13 of the insulating core 14 and the bushing 29 is formed with an externally screw threaded outer wall for engaging the inner screw threaded wall of the front chamber 7. Upon the outer edge of the bushing or locking ring 29 is formed the broad annular head 30, which overhangs 55 the inner smooth wall of the bushing 29 to provide the inner annular shoulder 31, the head also overhanging the screw threaded outer wall of the bushing 29 to provide the outer annular shoulder 32, the periphery 60 of the head 30 of the bushing 29 being pref-

erably formed hexagonal for receiving a suitable wrench, so that, when the bushing or locking ring 29 is screwed inwardly, the inner shoulder 31 of its head 30 will bind against the washer 33 interposed between the shoulder 31 and the annular shoulder 34 formed between the head 13 and the body portion of the insulating core 14, and the outer shoulder 32 of the head 30 of the bushing 29 will bind against the washer 35 interposed between the shoulder 32 and the outer end of the plug or housing 4, though the washer 35 may be omitted if desired, and at the same time the inner end of the bushing 29 will bind against the washer 36 interposed between the inner end of the bushing 29 and the flange 11 of the heater 9 on the one side and the front wall of the annular rib or shoulder 8 within the plug or housing 4, whereby the heater 9 and the insulating core 14 and their accessories are firmly secured in operative position within the plug or housing 4, and at the same time the washers 33, 35 and 36 provide a tight joint at their respective locations for preventing any leakage of the liquid fuel from the carburetor bowl 1 through the heating device, and which washers are preferably formed of soft copper though the same may be formed of or combined with any other suitable material that will provide a liquid tight joint.

For energizing the coil 16 the positive wire 37 is provided which leads from any suitable source of electrical supply controlled by a suitable switch, and has one end suitably secured to the threaded end 25 of the metal core or stem 18 and held firmly between the cup shaped nut 26 and the binding nut 27 upon the threaded end 25 of the metal core 18. The current from the wire 37 is conducted through the metal core 18 to the heating coil 16 for energizing the same, and is thereafter conducted from the inner end of the coil 16 through the metal portion of the heater 9, the bushing 29, the plug or housing 4, and the wall of the carburetor bowl 1 to the binding post 38, provided with the binding screw 39, and thence returned to the source of electrical supply through the return wire 40 having one end suitably secured to the binding post 38 and between the same and the binding nut 39. While I prefer to return the current from the heating coil 16 in the manner just described, the current, however, may pass from the carburetor bowl to the engine construction or frame work thereof and then be returned to the source of electrical supply or the same may be grounded in any suitable manner desired.

The metallic portions of the parts constituting the invention may be formed of any suitable material, but I preferably form the shell of the heater 9 of brass, the flange 130

11 and cap 12 thereof of steel, and the insulating core 14 and the insulating lining 15 within the heater 9 may be formed of any suitable insulating material, but I preferably form the core 14 of porcelain, and the lining 15 of mica.

While the manner of positioning the heating device with respect to the carbureter bowl, as disclosed in the drawings, is shown for the sake of illustration and clearness, I desire it to be understood that I am not restricted to this exact positioning of the heating device upon the carbureter bowl, as the screw threaded opening 2 in the wall of the carbureter bowl 1 may be formed at any other desired and suitable point in the wall of the carbureter bowl, either formed in any of the carbureters now in use or formed in the same during their course of manufacture, and the heating device capable of being mounted in the screw threaded opening in the wall of the carbureter bowl in either case, whereby the liquid fuel within the carbureter bowl will surround the heater and be efficiently heated thereby.

Having described my invention, what I claim as new and desire to secure by Letters Patent, is:—

1. In combination with a carbureter bowl having a threaded opening, a heating device comprising a housing having a threaded extension positioned in the threaded opening of the carbureter bowl, an annular shoulder formed within the housing, an insulating core in the housing, a casing positioned in the housing and having a portion thereof engaging the shoulder, one end of the casing extending beyond the inner end of the housing and terminating within the carbureter bowl, a conducting element extending through the core, a heating element within the casing, one of the ends of the heating element making connection with the conducting element, the opposite end thereof extending through the casing, and means coöperating with the annular shoulder for holding the casing in position in the housing.

2. In combination with a carbureter bowl having a threaded opening, a heating device

comprising a housing having an internal shoulder formed intermediate the length thereof, a cylindrical heater element having a shoulder, positioned in the housing and spaced from the interior walls thereof to 55 form a chamber, means coöperating with the shoulders for holding the heater element in position, an insulating core having a central metallic core positioned in one end of the heater element, a heating coil within the 60 cylindrical heater element, one end of the coil extending through the heater element, and an enlarged head for holding the opposite end of the heating coil in engagement with the central metallic core. 65

3. In a device of the character described, the combination with a carbureter bowl containing a liquid fuel, of a housing secured through a wall of said carbureter bowl, an insulating core having one end 70 partially positioned within said housing, a metallic casing also partially positioned within said housing and having one end embracing that portion of the insulating core within said housing for supporting 75 said casing in suspended position, an insulating lining within said casing, a metallic locking ring embracing that portion of said metallic casing upon said insulating core, a metallic core within said insulating core, a 80 heating coil within said casing having one of its ends projecting through the closed end of said casing and secured to the metallic portion thereof, and its opposite end secured upon one end of said metallic core, and 85 means for connecting the opposite end of said metallic core to a source of electrical supply for establishing a circuit through said heating coil and the metallic parts in interconnection therewith for energizing 90 said coil for rendering the same active for heating said liquid fuel.

In testimony whereof I have signed my name to this specification in the presence of two subscribing witnesses.

JOHN HENRY LEPPER.
